[57] CLAIM

The ornamental design for a cup or similar article, as shown and described.

DESCRIPTION

FIG. 1 is a side, elevational view of a cup or similar article embodying my new design;

FIG. 2 is a front elevational view thereof as seen from the right of FIG. 1;

FIG. 3 is a side elevational view thereof opposite that shown in FIG. 1;

FIG. 4 is a rear elevational view thereof as seen from the left of FIG. 1; and

FIG. 5 is a top plan view thereof.

The bottom foot area of the cup is conventional and is unornamented.

The characteristic feature of the design resides in the particular surface decoration shown on the exterior cup wall in FIGS. 1-4.
